CLAIM

The ornamental design for a bracket for mounting on a wall for supporting the butt ends of vertically oriented fishing rods, as shown and described.

DESCRIPTION

FIG. 1 is a perspective view of a bracket for mounting on a wall for supporting the butt ends of vertically oriented fishing rods showing my new design, it being understood that the broken lines are for illustrative purposes only;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view taken from the left of FIG. 4, the side opposite being a mirror image thereof.

Fig. 1**Fig. 2****Fig. 3****Fig. 4****Fig. 5****Fig. 6**
